Michael Kilgour & Moore

UNITED STATES PATENT OFFICE.

HAUGHTON BROWN, OF MINNEAPOLIS, MINNESOTA.

BROOM.

Application filed March 26, 1921. Serial No. 455,723.

To all whom it may concern:

Be it known that I, HAUGHTON BROWN, am a citizen of the United States, residing at Minneapolis, in the county of Hennepin 5 and State of Minnesota, have invented certain new and useful Improvements in Brooms; and I do hereby declare the following to be a full, clear, and exact description of the invention, such as will enable 10 others skilled in the art to which it appertains to make and use the same.

My invention has for its object to provide an improved broom structure which will be highly efficient in use and which may be 15 constructed at small cost. The invention is illustrated in the accompanying drawings, wherein like characters indicate like parts throughout the several views.

Referring to the drawings:

20 Fig. 1 is a plan view illustrating the first step in the construction of the broom;

Fig. 2 is a plan view illustrating a later step in the construction of the broom;

25 Fig. 3 is a perspective with some parts broken away, showing the broom completed, except for the application of a protecting cap;

Fig. 4 is a plan view with some parts broken away, showing the completed broom; 30 and

Fig. 5 is a perspective showing a portion of the broom handle and its anchoring bar.

As the first step in the formation of the broom, a layer of broom corn 6, the head 35 ends of which have been dipped in tar, creosote or similar adhesive material, is properly laid with its dipped ends on a binding strap 7. This binding strap 7 is preferably a strip of fine wire screen, which gives the best results because of strength and extreme porosity, (see Fig. 1). Preferably, in laying down the first complete layer of straw 6, the finer straws are first laid on the screen 40 strap 7 and then a layer of coarser straw is laid on the fine layer.

The numeral 8 indicates the broom handle, the same, at its lower end, having a slotted anchoring bar 9. The broom handle is then laid, as shown in Fig. 2, with its lower end 50 and with its anchoring bar 9 pressed flat-

wise upon the dipped ends of the broom straws 6. Then, the other half of the broom body is completed preferably by laying, first, a thin layer of coarse straw and then a thin outer layer of fine straw upon the layer 6 55 and anchoring bar 9, and then the ends of the binding strap 7 are turned over and pressed down, as shown in Fig. 3. Said binding strap and the dipped ends of the broom straws are preferably placed in a 60 press or vise and tightly compressed to compact form, and when the adhesive material has set, the broom straws will be very firmly united together and to the broom handle and binding strap. 65

The broom is then completed by the application of a flattened cap or head 10, the crown of which has a hole adapting it to be slid over the broom handle and the body of which fits closely around the flattened 70 upper portion of the broom body. Nails or rivets 11 are then preferably driven through the hood, the binding strap 7 and the head of the broom body. If nails are used, they should be clinched to hold them in position. 75 Below the cap, the broom body is preferably bound together by a row of stitches 12.

The hood or cap 10 will usually be made of heavy, tough, vulcanized paper or cardboard, but may be made of other materials 80 and, for some purposes, will be made from thin sheet metal. This not only gives a neat appearance to the broom, but protects the head of the broom and re-inforces the connection between the broom body and handle. 85 In actual practice, these brooms have been found highly efficient, strong and durable.

What I claim is:

1. A broom comprising a bundle of broom straw, the butt ends of the straw being coated with adhesive material, an anchor bar imbedded in the butt end of said straw, a handle secured to said anchor bar, a binding strap of woven wire fabric surrounding and secured to the coated butt ends of broom straw. 90

2. The construction defined in claim 1 in further combination with a cap placed around said broom handle and around said binding strap and secured in position. 100

3. The construction defined in claim 1 in further combination with a cap placed around said broom handle and around said binding strap, said cap, binding strap and broom straws being flattened out, and nails driven through said cap, binding strap and coated ends of the layers of broom straw.

4. The construction defined in claim 3 in which certain of said nails are also passed through the anchoring bar of said broom handle thereby positively anchoring together the several elements of the broom.

In testimony whereof I affix my signature.
HAUGHTON BROWN.
